A. J. HORTON.
MOTOR CONTROLLER.
APPLICATION FILED MAY 4, 1908.

1,108,439.

Patented Aug. 25, 1914.

UNITED STATES PATENT OFFICE.

ALBERT J. HORTON, OF WHITE PLAINS, NEW YORK, ASSIGNOR TO THE CUTLER-HAMMER MFG. CO., OF MILWAUKEE, WISCONSIN, A CORPORATION OF WISCONSIN.

MOTOR-CONTROLLER.

1,108,439.

Specification of Letters Patent. Patented Aug. 25, 1914.

Application filed May 4, 1908. Serial No. 430,829.

To all whom it may concern:

Be it known that I, ALBERT J. HORTON, a citizen of the United States, residing at White Plains, in the county of Westchester 5 and State of New York, have invented new and useful Improvements in Motor-Controllers, of which the following is a full, clear, concise, and exact description, reference being had to the accompanying drawings, forming a part of this specification.

My invention relates to improvements in speed controllers for electric motors. It applies more particularly to speed controllers that are automatically operated.

The object of my invention is to provide means whereby the controller may be set to cause the motor to operate at different pre-determined speeds.

Other objects of my invention will herein-after appear.

In accordance with the preferred form of my invention, I provide a speed controller with means for adjusting the same to cause the motor to operate at different pre-determined speeds.

The accompanying drawing illustrates one simple form of my invention, which I have worked out in practice. Of course, other forms may be developed.

The views in the accompanying drawings are as follows: Figure 1 is a general view of the controller, parts thereof being shown in section. Fig. 2 is a detailed view of the adjusting pin. Fig. 3 is a view of the adjusting screw for the dash pot.

As I have already said, my invention may be embodied in various different forms. The one which is illustrated in the drawing has been selected as a simple illustration of my invention. I shall now proceed to describe the device which is illustrated in the accompanying drawing, it, of course, being understood that various changes may be made therein in practice.

The parts of the controller are preferably mounted upon a base 1. The arm or switch 2 is pivoted upon a pin 3 protruding from the base 1. This arm is adapted to sweep over a series of contacts 4 connected to an armature resistance 5, and also a series of contacts 6 connected to a field resistance 7. The arm first passes over the contacts 4, and then over the contacts 6. While the arm is passing over the contacts 4 it also

engages a segment 8, and while it is passing

over the contacts 6 engages a segment 9. The downward movement of the arm is limited by a pin 10 mounted upon the base 1. The arm 2 is operated by a solenoid having a winding 11, and a movable core 12. The 60 movable core is connected to the arm by means of an insulating link 13, which is pivoted to said arm and to the lower end of the said movable core. The solenoid winding is wound upon an insulating spool 65 14, which is mounted within a magnetic frame 15, secured to the panel 1. The winding is held in place in the frame by means of a non-magnetic tube 16, which is inserted through a hole in the bottom of the 70 frame 15, and passes upward through the winding and fits against a shoulder in a recess in the upper part of the frame. This tube is held in place by means of a screw 17, threaded in the lower part of the frame, 75 and having its head bearing against the lower end of the non-magnetic tube. The movable core 12 slides within the non-magnetic tube. Within the upper end of the tube is an adjustable stationary core 18, 80 which serves as a stop for limiting the upward movement of the movable core, and which always magnetically seals with the same at the limit of its movement. The stationary core forms part of the magnetic 85 circuit, and, as aforesaid, serves as a stop for the movable core. The stationary core is supported by an arm 19, pivoted upon a pin 20. The central portion of the arm is provided with an opening 21 through 90 which extends a tube 22, which is threaded into the stationary core. The upper end of the tube 22 is provided with a flange 23, which bears upon the upper portion of the arm 19. The outer end of the arm 19 is 95 provided with a sliding pin 24 which is adapted to enter in one of the series of holes 25 in a curved bar 26 mounted upon the panel 1. The pin 21 is pressed inwardly by a spring 27. It will be observed that the 100 arm 19 may be set in different positions by inserting the pin in different holes in the bar 26. If the position of the arm 19 be thus changed, obviously the position of the stationary core 18 will be changed, and 105 hence the upward limit of the movement of the movable core will be varied. The arm 19 may be, therefore, set to adjust the device so that the arm 2 will stop at any desired position. Through the sta- 110

tionary core 18 and the tube 22 passes a non-magnetic pin 28, the upper end of which is provided with a head 29, that bears upon the flange 23. To a lug 30 on 5 the arm 19 is pivoted a switch 31, the free end of which bears upon a contact 32, mounted upon the panel 1. The purpose of this switch is to short circuit a resistance when it engages the contact 32. When the 10 movable core is raised by the winding, it strikes the pin 28, which in turn opens the switch 31, which causes a resistance to be inserted in the circuit of the winding 11. The structure is such that this function will 15 be accomplished irrespective of the position in which the stationary core may be set. The switch arm 2 is connected to the piston of a dash pot 33, which is pivoted upon the base 1. The dash pot is provided with an 20 adjusting screw 34 for adjusting the rate of travel of the dash pot. Of course, the dash pot may be of various forms. For convenience of illustration, I have illustrated the screw 34 as provided with a V-shaped 25 slot in its side.

For the purpose of convenience of illustration I have diagrammatically illustrated one arrangement of circuits that may be used with the controller. Of course, various 30 circuit arrangements may be employed. I shall now proceed to describe the operation of the controller. Assume that the arm 19 is set in the position shown. If the main line switch 35 be closed, current will flow 35 from the positive line through conductor 36, through switch arm 2, resistance 5, conductor 37, motor armature A, conductor 38, to the negative line. Current will also flow from the switch arm 2 to contact segment 8, thence 40 through conductor 39, and field F of the motor to the negative line. The closure of the main circuit will also close the circuit through the solenoid, which circuit extends from the conductor 36, through conductor 45 40, winding 11, conductor 41, conductor 42, arm 19, switch 31, contact 32, conductor 43 and conductor 44 to the negative line. The solenoid will raise the movable core 12, thereby moving the switch arm 2 upward, 50 and removing resistance 5 from the armature circuit. When the movable core strikes the stationary core, the switch arm 2 will stop. With the arm 19 in the position shown in the drawing, only part of the armature 55 resistance will be cut out, and hence the motor will be operated at a slow speed. The core 12 will operate the pin 28 as it approaches the stationary core, which pin will open switch 31. The resistance 45 will then 60 be inserted in the circuit of the winding 11, and this circuit will extend through the conductor 40, winding 11, conductor 41, conductor 46, resistance 45 and conductor 44 to the negative line. If it be desired to set the 65 controller for the motor to operate at a

higher speed, the arm 19 may be raised so as to raise the stationary plunger. Then the movable core will be permitted to rise higher and draw the switch arm 2 over more of the contacts 5. The arm 19 may be set so high 70 as to permit the switch arm to pass first over the contacts 4 and then over the contacts 6, in which event, after the armature resistance 5 has been removed from circuit, the switch arm will insert the resistance 7 in 75 the field circuit, as it passes over the contacts 6, thereby raising the speed of the motor to its highest degree. It will be observed that I have provided an automatic speed controller which may be set to limit the operation of the motor to any desired predetermined speed.

Having thus described my invention, what I claim as new and desire to secure by Letters Patent, is:

1. The combination with a solenoid operated speed regulator, of means associated therewith to limit the movement of said regulator at will to obtain any one of a number of different predetermined speeds of the 90 motor, the operating solenoid having a movable plunger arranged to always magnetically seal when the regulator reaches the limit of its movement.

2. The combination with a speed controller for electric motors, of an operating solenoid having a relatively stationary core, and a movable core connected to said controller for operating the same, means including said relatively stationary core for limiting the movement of said controller and varying the range of movement thereof at will, whereby said controller may be caused to automatically bring the motor up to any one of a number of different predetermined 105 speeds.

3. In a speed controller for electric motors, the combination with a controlling member, of an electromagnetic winding, a movable core within said winding and connected to said controlling member, a stationary core within said winding, one of said cores being adjustable relative to the other for limiting the range of movement of said controlling member, to cause the motor 110 to operate at different predetermined speeds.

4. In combination, a speed controlling rheostat, a solenoid having a stationary core and a movable plunger, said movable plunger being connected to the movable element of 120 said rheostat, said stationary core being arranged to serve as a step for said movable plunger, means for setting said stationary core at different positions to vary the range of movement of the movable element of said 125 rheostat.

5. The combination with an electromagnetically operated speed controller, of means for adjusting the same at will to cause the motor to operate at a predetermined speed,

and automatically operated means for reducing the flow of current through the operating magnet after the controller has been operated.

5 6. In a controller for regulating the speed of electric motors, the combination with a controlling member, of an electromagnetic winding, a movable core within said winding and connected with said controlling member, 10 a stationary core within said winding serving as a stop for said movable core, one of said cores being adjustable relative to the other to limit the movement of said controlling member, and means for reducing the flow of current through said winding when said controlling member has reached the limit of its travel.

7. In combination, a speed controlling rheostat, a solenoid having a stationary core 20 and a movable core, said movable core being connected to the movable element of said rheostat, said stationary core being arranged to serve as a stop for said movable core, means for setting the stationary core 25 at different positions to vary the range of movement of the movable element of said rheostat, and means for reducing the flow of current through said solenoid after said rheostat has been operated irrespective of 30 the position of said stationary core.

8. In a controller for regulating the speed of electric motors, the combination with a controlling member, of a solenoid having a movable plunger connected with said controlling member, and a stationary plug serving as a stop for said movable plunger, a switch adapted to be operated by said plunger upon reaching its final position, a resistance for said solenoid controlled by said 40 switch, and means for adjusting the position of said plug and said switch to cause the motor to operate at different predetermined speeds.

9. In a speed controller for electric motors, the combination with a controlling member, a solenoid having a movable core connected with said controlling member, and an adjustable plug for limiting the movement of said movable core, a lever supporting said adjustable plug, means for locking said lever in different positions, a switch carried by said lever, a resistance for said solenoid controlled by said switch, and means actuated by said core upon reaching 55 its final position for opening said switch.

10. In a speed controller for electric motors, in combination, a resistance, a controlling member therefor, a solenoid having a relatively stationary core and a movable 60 core connected to said controlling member for operating the same, and means including said relatively stationary core for limiting the movement of said controlling member and varying the range of movement thereof at will to cause the motor to be auto-

matically brought up to any one of a number of different predetermined speeds, said movable core and said stationary core being adapted to always magnetically seal when said controlling member reaches the limit 70 of its movement.

11. In a speed controller for electric motors, in combination, an armature resistance, a field resistance, a single movable member for controlling both of said resistances, a 75 solenoid for operating said controlling member, said solenoid having a relatively stationary core and a movable core connected to said controlling member, and means including said relatively stationary core for 80 limiting the movement of said movable core and varying the range of movement of said controlling member at will to obtain different predetermined maximum speeds of the motor upon operation of said controlling 85 member.

12. In a speed controller for electric motors, the combination with a field resistance, of an armature resistance, a single controlling member for both of said resistances, an 90 electromagnet, a movable core and a stationary core mounted therein, said movable core being connected to said controlling member, said stationary core being arranged to limit the movement of said movable core, 95 and means for adjusting one of said cores relative to the other for varying the range of movement of said controlling member.

13. The combination with a speed controller for electric motors of an operating 100 solenoid having a relatively stationary core and a movable core connected to said controller, means including said relatively stationary core for limiting the movement of said controller and varying the range of 105 movement thereof, said movable core always abutting against said stationary core upon energization of said solenoid, and means for automatically reducing the flow of current through said solenoid upon said 110 movable core reaching the limit of its movement.

14. In a speed controller for electric motors, in combination, a resistance, a controlling element therefor, an operating 115 winding having a relatively stationary core, and a movable core connected to said controlling element, means including said relatively stationary core for limiting the movement of said movable core, and varying the 120 range of movement thereof at will to cause said resistance to be varied to obtain any one of a number of different predetermined speeds of the motor upon energization of said winding, and a switch adapted to be 125 operated upon said controlling element reaching any predetermined final position, to insert resistance in circuit with said winding to reduce the flow of current therethrough.

15. In a speed controller for electric motors, the combination, with a controlling member, of a solenoid winding having a movable core connected with said controlling member, an adjustable plug within said winding for limiting the movement of said movable core, and an adjustable lever supporting said plug and adapted to be locked in different positions to cause said plug to stop said plunger in any one of a number of

different positions to cause the motor to operate at different predetermined speeds.

In witness whereof, I have hereunto subscribed my name in the presence of two witnesses.

ALBERT J. HORTON.
